United States Patent Office

Des. 224,890
Patented Oct. 3, 1972

224,890

CONSTRUCTION BLOCK

George B. Muse, Hillcrest Drive, Calhoun, Ga. 30701

Filed Oct. 6, 1970, Ser. No. 25,356

Term of patent 14 years

Int. Cl. D25—01

U.S. Cl. D18—2

FIG. 1

FIG. 2

FIG. 3

FIG. 4

FIG. 1 is a perspective view of a construction block embodying the design, and showing the top, rear and right-hand end of the construction block;

FIG. 2 is a bottom plan view of the block construction shown in FIG. 1;

FIG. 3 is a front elevational view of the construction block shown in FIG. 1; and

FIG. 4 is a left-hand end elevational view of the construction block shown in FIG. 1.

I claim:

The ornamental design for a construction block, substantially as shown.
